L. G. BOWEN.

OIL SAVER.

APPLICATION FILED JUNE 17, 1916.

1,215,244.

Patented Feb. 6, 1917.

UNITED STATES PATENT OFFICE.

LESLIE G. BOWEN, OF KANSAS CITY, MISSOURI.

OIL-SAVER.

1,215,244.

Specification of Letters Patent. Patented Feb. 6, 1917.

Application filed June 17, 1916. Serial No. 104,271.

To all whom it may concern:

Be it known that I, LESLIE G. BOWEN, a citizen of the United States, residing at Kansas City, in the county of Jackson and State of Missouri, have invented certain new and useful Improvements in Oil-Savers, of which the following is a specification.

My invention relates to oil savers, and one object is to provide a simple and inexpensive device of this character to prevent oil escaping from the top of flowing wells during the drilling operation.

A further object is to provide a device of this character which is releasably retained in place at the top of a well, so that when contacted by a tool, such as a drill, bailer, etc., during the removal thereof from the well, no injury will result either to my device or the tool.

Other objects will hereinafter appear, and in order that the invention may be fully understood, reference will now be made to the accompanying drawing, in which:

Figure 1 is a vertical section of the device applied to the casing head of a well.

Fig. 2 is a horizontal section on line II—II of Fig. 1.

Fig. 3 is a detail of a latch employed in carrying out the invention.

Fig. 4 is a broken horizontal section of a plunger constituting a part of the invention.

Referring now in detail to the various parts, A designates the well casing surrounded by the usual casing head B.

1 designates my closure device which embodies a shell 2 provided with a circular flange 3, adapted to be reliably held upon a seat C in the casing head B, by latches 4 and screws 5.

6 designates a plunger slidable in the shell 2 and provided at its upper threaded end with a collar 7, which limits downward movement of said plunger. When the plunger 6 is at the end of its downward movement the collar 7 rests upon a packing ring 8, whereby suitable packing 9 is held in position to seal the joint between the shell 1 and the plunger 6.

The plunger 6 which is, preferably, cylindrical in form has a plurality of grooves 10 of T-form in cross section and having inner walls 11 converging downwardly toward each other, as disclosed by Fig. 1.

The latches 4 are arranged radially about

the vertical axis of the plunger 6 and embody stems 12 extending into the grooves 10 and terminating at their ends in T-heads 13, which extend into the lateral portions 14 of the grooves 10, so that the walls thereof may draw the latches inward when the plunger 6 moves upward, and push said latches outward when said plunger moves downward. Recesses 15 are provided in the circular flanges 2 to admit of the latches 4 moving inward out of contact with the screws 5, which overlap the beveled outer sides 16 of said latches 4 when the parts are in normal position, as disclosed by Fig. 1.

The plunger 6 has a central bore 17 for the free passage of the cable D, which works freely up and down in said bore during the drilling operation. The lower end of the cable D is provided with the usual socket E to which a drill, bailer, or other tool may be attached. Oil is prevented from flowing upward through the bore 17 by packing 18 held in the plunger 6 by a gland 19 provided at its upper end with a hand wheel 20, whereby it may be adjusted to force the packing around the cable D. Care, however, is taken not to compress the packing 18 around the cable D tight enough to cause it to lift the closure from its seat C in the casing head B, when the cable moves upward.

In practice, when the closure is in position in the casing head B, the operation of the cable D whether drilling, bailing, etc., proceeds in the usual manner, but when the tools are to be withdrawn they are raised and on contacting the underside of the plunger 6, force the same upward to the dotted position, Fig. 1, causing it through the intermediacy of the inclined walls of 95 the grooves 10 to draw the latches 4 inward from beneath the screws 5, so that the closure can move upward with the tool. When thus removed, the closure remains on the cable and above the tool, so that when the latter is again introduced into the well, the lowering of the cable results in seating the closure in the casing head B.

From the foregoing description, it is apparent that I have produced a simple and inexpensive device possessing the features of advantage above enumerated, and while I have shown and described the preferred form of my invention, I reserve the right to make such changes in the construction, 110

proportion, and arrangement of parts, as properly fall within the spirit and scope of the claims.

Having thus described my invention, what I claim and desire to secure by Letters Patent, is:

1. The combination of a casing head, a closure for said casing head, releasable means for securing said closure to the casing head, and means slidable in the closure and provided with downwardly converging grooves the walls of which control said releasable means.
2. The combination of a casing head, a closure for said casing head, releasable means for securing said closure to the casing head, said means being provided with T-shaped terminals, and means slidable in the closure and provided with converging grooves to receive said T-shaped terminals and control the releasable means.
3. The combination of a casing head, screws in the upper portions thereof, latches

slidable in the closure and having beveled outer terminals for engagement with said screws, and means slidable in the closure and engaging the inner terminals of said latches to move the same in and out of engagement with the casing head.

4. The combination of a casing head, a closure for said casing head, latches slid-
able in said closure and adapted to secure the same to the casing head, a plunger slid-
able in the closure and having grooves with
walls engaging the latches to move the same
in and out of engagement with the casing
head, means to limit the movement of said
plunger, and packing between the plunger
and the closure.

In testimony whereof I affix my signature, in the presence of two witnesses.

LESLIE G. BOWEN.
